UNITED STATES PATENT OFFICE.

VINTON E. SISSON, OF CHICAGO, ILLINOIS, ASSIGNOR TO WALTER P. MURPHY, OF CHICAGO, ILLINOIS.

PRESSED-STEEL CAR END.

1,237,397.

Specification of Letters Patent. Patented Aug. 21, 1917.

Application filed April 13, 1914. Serial No. 831,533.

To all whom it may concern:

Be it known that I, VINTON E. SISSON, a citizen of the United States, residing at Chicago, in the county of Cook and State 5 of Illinois, have invented certain new and useful Improvements in Pressed-Steel Car Ends, of which the following is a specification.

My invention relates to an end structure 10 for railway cars particularly for box cars, and has for its object to provide an end structure for a railway car composed of sheet metal and formed with one or more pressed ribs, corrugations or reinforcing 15 members, which extend across the end from one edge to the other so as to constitute truss-like elements transmitting stresses received by the end structure, for example, the thrusts and pressures due to shifting 20 cargoes, to the end frame of the car, and preferably formed also on opposite sides of said truss-like corrugation or corrugations, with a plurality of pressed ribs or corrugations arranged so that they transmit stresses 25 exerted against them to said truss-like corrugation or corrugations and to the end frame of the car; this arrangement of stiffening and reinforcing ribs or corrugations resulting in an end structure which is very 30 strong, rigid and durable, and at the same time light in weight and inexpensive to manufacture.

The invention is illustrated, in two preferred embodiments, in the accompanying 35 drawings, wherein—

Figure 1 is an end elevation of the body of a box car provided with a sheet metal car end embodying one typical form of the invention;

Fig. 2, a sectional view taken on line 2—2 of Fig. 1;

Fig. 3, a detail sectional plan on line 3—3 of Fig. 1;

Fig. 4, a view, similar to Fig. 1, illustrating a modified form of the invention;

Fig. 5, a sectional view on line 5—5 of Fig. 4, and

Fig. 6, a sectional plan taken on line 6—6 of Fig. 4.

Like characters of reference designate like parts in the several figures of the drawings.

In the preferred embodiments of my invention shown in the accompanying drawings, the end structure consists of a single

sheet of metal 10 designated in Figs. 1 to 3 inclusive and 11 in Figs. 4 to 6 inclusive, which is secured, in each case, to the end frame of the car in any suitable manner. For example, I have shown the sheet in each 60 construction as formed with angular flanges 12 overlapping the corner posts 13 of the car and secured thereto by bolts 14, the upper edge of the sheet being secured to the end plate 15 by bolts 16 and the lower edge 65 being formed with an inturned flange 17 intervening between the flooring 18 and the end sills 19 and secured to the latter by through bolts 20. In the construction shown in Figs. 1 to 3 inclusive, the sheet 10 is 70 formed with two sets of vertical corrugations 21 and 22, preferably pressed inwardly from the plane of the sheet and between the same and running transversely thereto, a truss-like corrugation 23 which is preferably 75 pressed outwardly and is preferably widest and deepest at the center and tapered down toward its extremities. The truss-like corrugation 23 is preferably arranged in the same plane with the side girders 24 80 of the car so that it will transmit the stresses which it receives to said side girders. In order to obtain the full benefit of this arrangement, angle irons 25 may be riveted to the end sheet at the extremities of the corrugation 23 and attached to the side girders 85 24 by through bolts 26 (Fig. 3).

If the car be constructed with two side girders on each side instead of one, the construction of the end may, if desired, be modified accordingly so that there will be two horizontal truss-like corrugations 23 instead of one, and three sets of vertical corrugations. Such construction is shown in Figs. 90 4 to 6 inclusive. In this construction the 95 horizontal or truss-like corrugations 27, instead of being formed in the sheet 11, are pressed out of separate bands or girth members 28. The sheet 11 is formed with three sets of vertical corrugations 29 and between 100 these with flat spaces for the truss or girth members 28. The latter are formed with angular flanges 30 which are prolonged beyond the angular flanges 12 of the sheet and secured to the side girders 31 by bolts 32 105 or other suitable means.

The heaviest thrusts and pressures against the end of a freight car are caused by the shifting of heavy articles of the cargo such as rails, pipe, and the like, which are placed 110

close down to the floor. With the end provided with vertical corrugations terminating near the lower edge of the sheet so as to leave a flat margin for attachment to the frame of the car there is danger that impacts against the lower portion of the sheet will stretch or break the marginal portion of the sheet so as to make the end of the car leaky. In the constructions shown the in-turned flange 17 of the lower sheet prevents this the flange not only serving as a convenient means for attaching the end structure to the sill with a joint which will be grain proof, but also reinforcing the sheet at the place where, for the reasons above stated, reinforcement is particularly necessary.

While I have described my invention in certain preferred embodiments, some modification in the form, construction and arrangement of the parts as shown and described might be made without departure from the principle of the invention. Therefore I do not wish to be understood as limiting the invention to the particular constructions, arrangements and devices herein shown except so far as certain of the claims herein are so limited by their express language.

30 I claim:

1. The combination with the end frame of a railway car, of a sheet metal end for the car comprising a single sheet of metal extending from top to bottom and from side to side of the car, formed with two sets of corrugations and provided with a separate reinforcing band extending across said end sheet between said sets of corrugations, said band overlapping the outer side of said frame.

2. The combination with the end frame of a railway car, of a sheet metal end for the car comprising a single sheet of metal extending from top to bottom and from side to side of the car, formed with two sets of corrugations and provided with a separate reinforcing band extending across said end sheet between said sets of corrugations and provided with a longitudinally disposed corrugation, said band overlapping the outer side of said frame.

3. The combination with the end frame of a railway car, of a sheet metal end for the car comprising a single sheet of metal extending from top to bottom and from side to side of the car, formed with two sets of corrugations and provided with a separate reinforcing band extending across said end sheet between said sets of corrugations and provided with a longitudinally disposed corrugation which is largest at the middle and tapers toward its ends, said band overlapping the outer side of said frame.

4. The combination with the end frame of a railway car, of a sheet metal end for the

car comprising a single sheet of metal extending from top to bottom and from side to side of the car formed with upper and lower sets of vertical corrugations and provided with a reinforcing band which extends 70 across the end between said upper and lower sets of vertical corrugations.

5. The combination with the end frame of a railway car, of a sheet metal end for the car comprising a single sheet of metal extending from top to bottom and from side to side of the car formed with upper and lower sets of vertical corrugations and provided with a reinforcing band which extends 75 across the end between said upper and lower 80 sets of vertical corrugations and is formed with a longitudinal corrugation.

6. The combination with the end frame and side girders of a railway car, of a sheet metal end for the car comprising a single metal sheet formed with upper and lower sets of vertically arranged corrugations, and provided with a corrugation which is disposed between said sets of corrugations and extends from side to side of the car.

7. The combination with the end frame and side girders of a railway car, of a sheet metal end for the car comprising a single metal sheet formed with upper and lower sets of vertically arranged corrugations, 95 and provided with a corrugation which is disposed between said sets of corrugations and extends from side to side of the car and terminates adjacent the said side girders so as to transmit stresses thereto.

8. The combination with the end frame of a railway car, of a sheet metal end for the car comprising a single metal sheet provided with means for attaching it to said end frame and formed with two sets of inwardly pressed corrugations and provided with an outstanding corrugation between said sets of corrugations which extends transversely thereto.

9. The combination with the end frame of a railway car, of a sheet metal end for the car comprising a single metal sheet provided with means for attaching it to said end frame and formed with upper and lower sets of inwardly pressed vertical corrugations and provided with an outturned horizontal corrugation which extends across the end between said upper and lower sets of vertical corrugations.

10. The combination with the end frame of a railway car, of a sheet metal end for the car comprising a single metal sheet provided with means for attaching it to said end frame and formed with two sets of inwardly pressed corrugations and provided with an outstanding corrugation between said sets of corrugations, largest at the middle and tapered toward its extremities, which extends transversely thereto.

11. The combination with the end frame 130

- of a railway car, of a sheet metal end for the car comprising a single metal sheet provided with means for attaching it to said end frame and formed with upper and lower 5 sets of inwardly pressed vertical corrugations and provided with an outturned horizontal corrugation largest at the middle and tapered toward its extremities, which extends transversely thereto.
- 10 12. The combination with the end frame of a railway car, of a sheet metal end for the same comprising a single sheet of metal extending from top to bottom and from side to side of the car, and formed with upper and 15 lower sets of vertical corrugations, the ends of one set of corrugations being spaced away from the adjacent ends of the other set so as to provide a flat band extending across the end of the car from side to side.
- 20 13. The combination with the end frame of a railway car, of a sheet metal end for the same comprising a single sheet of metal extending from top to bottom and from side to side of the car and formed with upper 25 and lower sets of vertical corrugations, the ends of one set of corrugations being spaced
- away from the adjacent ends of the other set so as to provide a flat band extending horizontally across the end of the car substantially one-third of the way from the bottom 30 to the top of the end of the car, and a reinforcing element extending along said flat band and secured thereto.
14. The combination with the end frame of a railway car, of a sheet metal end for the same comprising a single sheet of metal extending from top to bottom and from side to side of the car and formed with upper and lower sets of vertical corrugations, the ends of one set of corrugations being spaced away 35 from the adjacent ends of the other set so as to provide a flat band extending horizontally across the end of the car substantially one-third of the way from the bottom to the top of the end of the car, and a reinforcing element extending along said flat band and secured thereto and to the outer sides of said end frame.

VINTON E. SISSON.
